MODEL CONSTRUCTION PANEL ASSEMBLY
Albin R. Sodergren, 42 Waterside Lane,
Clinton, Conn. 06413
Filed Sept. 23, 1964, Ser. No. 398,594
6 Claims. (Cl. 35—16)

This invention relates to a model construction panel assembly which may be used to give three-dimensional representation to the floor-plan layout of residential buildings and the like. More particularly, the present invention is designed and conceived to afford facility of erection and assembly in the presentation of scale model homes and similar buildings.

Frequently, it is desirable for real estate developers, architects, or construction contractors to be able to present to prospective purchasers a three-dimensional scalar representation of a proposed building for evaluation of its adequacy for its intended purpose and as an actual example for the discussion and consideration of proposed changes or alternative arrangements. Particularly with the rapid expansion of suburban living and the population movement out of urban areas in the United States, it is important that home purchasers and prospective home purchasers have available to them a three-dimensional scalar model to assess the suitability and desirability of a proposed plan layout as related to their individual needs. Architectural scale models have long been used to present designs to prospective home owners. While such architectural scale models are usually well executed and make a realistic representation, they are frequently limited in the extent and kind of change and rearrangement which they afford. Additionally, architectural scale models are generally quite expensive and are not readily adaptable to being disassembled into basic elements which can be re-used indefinitely to construct other designs of buildings.

Accordingly, it is an object of the present invention to provide a model construction panel assembly which is inexpensive in cost and is readily adaptable to assembly in a very broad variety of designs and forms.

Another important object of the present invention is to provide a model construction assembly of panels of like configuration which may be quickly assembled and disassembled.

Yet another object of the present invention is to provide a model assembly which, in addition to satisfying the above-stated objectives, presents a realistic, scalar representation including doorways, windows, closets and other such desirable construction details in a form which may be readily rearranged, changed or enlarged as desired.

These and other objects, features and advantages of the present invention will be more fully appreciated from the disclosure and description of the embodiments of the present invention which follows, together with the accompanying drawings in which:

FIGURE 1 is a perspective view of several panels assembled to represent part of the wall section of a building;

FIGURE 2 is a cross-sectional view of the partial wall of FIGURE 1 taken through section 2—2;

FIGURE 3 is a cross-sectional view of one type of panel which may be used in the assembly of the present invention;

FIGURE 4 is a cross-sectional view of an alternative type of panel which may be used in an assembly of the present invention;

FIGURE 5 is a top elevational view of a clip means which may be used to connect abutting panels in the assembly of the present invention;

FIGURE 6 is a side elevational view of the clip means illustrated in FIGURE 5; and

2

FIGURE 7 is a perspective view of a typical embodiment of the present invention in a model construction panel assembly of a small residential building.

The concept of the present invention includes a plurality of hollow, generally rectangular panels having two pairs of opposed side walls, each pair comprising side walls of identical dimensions. The pairs of side walls may be secured in spaced parallel relationship or may be an integral, extruded section of suitable material such as a light gauge metal or synthetic plastic, for instance. 5 The panels have at least one dimension which is common to all panels which is usually the smaller dimension of the two dimensions defining the rectangular cross-section. This common dimension permits the attachment 10 of a plurality of such panels by clip means securing the commonly dimensioned side walls in frictional abutment to form the wall sections of a building, for example. 15 The remaining side walls are preferably paired in identical sizes which vary from one panel to another so that 20 wall sections, windows, doorways, and other constructional details may be included in the assembly in any desired size by appropriate combination of panels of different lengths and heights. The panels preferably are of a semi-rigid synthetic plastic material which will permit 25 their being cut across their cross-section to any desired height as required. The panels are assembled by clip members of resilient material, such as light metal or plastic, which slidably engage contiguous side walls to hold them in frictional abutment. In a typical model 30 assembly of the present invention, such clip members will always engage at least one of the two side walls of each panel which has a dimension common to a pair of side walls of other panels.

Referring to FIGURE 1, there is shown in perspective 35 a partial wall structure of a scalar model assembly including the representation of a window. A plurality of panels 10, 11, 12, 13, 14 and 15 comprising pairs of opposed side walls 10a and 10b, 11a and 11b, 12a and 12b, 13a and 13b, 14a and 14b, and 15a and 15b are 40 secured in spaced parallel relationship by second pairs of opposed side walls all of which have the same cross-sectional width. This permits the insertion of clip members 16, 17, 18 and 19 to secure the contiguous panels in frictional engagement giving the assembly the appearance 45 of a typical flat wall surface of residential construction.

As will be seen in the cross-sectional view of FIGURE 2 the panels 13 and 15 have opposed side walls 13a and 13b, and 15a and 15b which have different panel lengths 50 than the opposed side walls 14a and 14b, and 10a and 10b of panels 14 and 10. This feature affords the convenience of assembling panels in varying arrangements to provide the desired size of windows, doorways, closets, and connected wall sections in accordance with any floor 55 plan layout of a residential home or other type building. The panels 10, 14, 15 and 13 as shown in the cross-sectional view of FIGURE 2 have remaining pairs of opposed side walls which all have a common dimension where the resilient clip members of the assembly of the present 60 invention are employed to join contiguous panels in frictional engagement in any desired configuration of model assembly.

FIGURE 3 illustrates a single panel cross-section comprising pairs of opposed side walls 20a and 20b, and 21a 65 and 21b, each pair of side walls being of identical dimensions. The side walls 21a and 21b each have right-angular flanges 21c and 21d extending from their side wall portions in a generally U-shaped configuration, which flanges are secured by suitable means such as cementing 70 or thermal bonding to the other pair of opposed side walls 20a and 20b.

FIGURE 4 shows an alternative type of panel which may be used in the assembly of the present invention. The panel of FIGURE 4, it will be noted, has two pairs of opposed side walls 22a and 22b, and 23a and 23b secured in spaced parallel relationship by reason of the integral construction of the panel which typically may be extruded synthetic plastic preferably of a semi-rigid type.

FIGURES 5 and 6 are top and side elevational views respectively, of a clip member 24 which may be employed in the assembly of the present invention. The clip 24 has a flat base portion 25 and a bent over upper portion 26 to form a generally U-shaped configuration and is of appropriate width to conveniently engage the smaller dimensions of contiguous side walls of the panels by sliding the clip member over contiguous side walls to secure them in frictional engagement in any desired arrangement.

FIGURE 7 shows a model construction panel assembly of the present invention in a perspectively viewed form of small residence 30. Included are the interior and exterior walls of the building, windows, doorways, closets, garage, etc. The manner in which different size panels may be readily combined to provide a desired result may be seen typically by comparing the different sizes of windows produced by combining panels 31 and 32 as contrasted to the larger combined panels 33 and 34. All the panels 31, 32, 33 and 34 are, however, of the same height to provide windows at the same wall level in a common wall which is usually the case in residential design. The panels 35 and 36 above the window are of the same combined over-all dimension as panels 31 and 32 below the same window and are of a suitable height to provide a conventional window opening to proper scale.

A plurality of panels 37, 38, 39 and 40 are secured in contiguous relationship by clip means in accordance with the concept of the present invention to provide the partial wall section over a garage door opening. The manner in which a plurality of panels of varied sizes may be combined in accordance with the teaching of the present invention is illustrated by the contiguous sections 41, 42, 43, 44, 45 and 46 which form a kitchen wall including a window placed as desired and in scaled proportions.

Those skilled in the art will appreciate that the assembly of the present invention comprises inexpensive elements which are readily adaptable to produce a very broad variety of scalar construction models which, when they have served their useful purpose, may be disassembled quickly for further use in different form and combination of assembly as desired.

The panels of the present invention may be of appropriate scale such as one-quarter or one-eighth scale for residential model assembly which would include panels of approximately one-half inch and one-quarter inch widths, respectively, to represent conventional frame construction of nominally two inch x four inch studding with appropriate sheathing.

Similarly, the panels of the present invention may be preferably scaled to represent the sixteen inches between centers of studs which is conventionally employed in much frame housing as required by many building codes. As will be apparent to those skilled in the art, panels having widths which are scalar incremental multiples of sixteen inches on centers frame construction, as well as one-half and one quarter wide panels representing sixteen inches on centers frame construction are preferably included among the elements comprising a kit for erecting construction model assemblies in accordance with the concept and spirit of the present invention. Panels should, of course, be of a variety of heights as well as lengths to afford the construction of scalar walls representing appropriate heights such as eight feet for homes, for instance, and windows approximately twenty-four to thirty inches from floor level.

As can be appreciated from the foregoing description and accompanying illustrations the present invention has

the advantages of being inexpensive, extremely versatile in use, affording quick and easy assembly and disassembly, is readily changed and/or rearranged to present a realistic three-dimensional scalar representation of model construction, as well as all of its elements being reusable for an indefinite number of times.

Since many changes could be made in the above construction and many apparently widely different embodiments of the invention could be made without departing from the scope or spirit thereof, it is intended that all matter contained in the above description or the accompanying drawings shall be interpreted as illustrative and not in a limiting sense.

Having thus described the invention, I claim:

1. A model construction panel assembly comprising a plurality of hollow, generally rectangular cross-section panels each including two pairs of opposed side walls, each pair of said opposed side walls being of identical dimensions and secured in parallel spaced relationship with the other pair of opposed side walls, one pair of said opposed side walls in each of said plurality of panels having at least one dimension common to one pair of side walls in each panel of said plurality of panels, and clip members of resilient material slidably engaging contiguous side walls of adjacent panels securing said panels in frictional abutment.

2. A model construction panel assembly comprising a plurality of hollow, generally rectangular cross-section panels, each including first and second pairs of opposed side walls, each pair of said opposed side walls being of identical dimensions and fixed in parallel spaced relationship by the other pair of opposed side walls, said first pair of said opposed side walls in each of said plurality of panels having at least one dimension common to all other first pairs of side walls in all said plurality of panels, and said second pairs of opposed side walls having dimensions selectable in accordance with the desired configuration of said model assembly and clip members of resilient material slidably engaging contiguous side walls of adjacent panels and securing said panels in frictional abutment.

3. A model construction panel assembly, comprising a plurality of hollow, generally rectangular cross-section panels, each constructed of a first pair of opposed side walls of uniform U-shaped cross-section secured to a second pair of side walls having identical dimensions, said panels being of selectable lengths in accordance with the desired configuration of said model assembly, and clip members of resilient material slidably engaging contiguous side walls of adjacent panels securing said panels in frictional abutment.

4. A model construction panel assembly comprising a plurality of hollow, generally rectangular cross-section panels each including two pairs of opposed side walls, each pair of said opposed side walls being of identical dimensions and secured in parallel spaced relationship with the other pair of said opposed side walls, one pair of said opposed side walls in each panel having at least one dimension common to one pair of side walls in each panel of said plurality of panels, said panels being dimensioned to represent in incremental scale a desired type of full-size wall construction, and clip members of resilient material slidably engaging contiguous side walls of adjacent panels securing said panels in frictional abutment.

5. A model construction panel assembly comprising a plurality of hollow, generally rectangular cross-section panels each including two pairs of opposed side walls, each pair of said opposed side walls being of identical dimensions and secured in parallel spaced relationship with the other pair of said opposed side walls, one pair of said opposed side walls in each panel having at least one dimension common to one pair of side walls in each panel of said plurality of panels, said panels being di-

mented to represent in incremental scale the full-size wall construction as required by building codes for the type of construction said model is to represent, and clip members of resilient material slidably engaging contiguous side walls of adjacent panels securing said panels in frictional abutment.

6. A model construction panel assembly comprising a plurality of hollow, generally rectangular cross-section panels each including two pairs of opposed side walls, each pair of said opposed side walls being of identical dimensions and secured in parallel spaced relationship with the other pair of said opposed side walls, one pair of said opposed side walls in each panel having at least one dimension common to a dimension of one pair of side walls in each panel of said plurality of panels, and

clip members of resilient material slidably engaging contiguous side walls of adjacent panels securing said panels in frictional abutment, said contiguous side walls engaged by said clip members including at least one side wall leaving a dimension common to a dimension of one pair of side walls of all said panels.
